(57) CLAIM

The ornamental design for an organizer rack, as shown and described.

DESCRIPTION

FIG. 1 is a top, front, right-side perspective view of an organizer rack showing my new design;

FIG. 2 is a front elevational view thereof;

FIG. 3 is a right side elevational view thereof, the left side
elevational view being a mirror image thereof;

FIG. 4 is a rear elevational view thereof;

FIG. 5 is a top plan view thereof; and,

FIG. 6 is a bottom plan view thereof.
